His Attorney

UNITED STATES PATENT OFFICE.

JAMES J. LARGENT, OF PEORIA, ILLINOIS, ASSIGNOR OF TWO-THIRDS TO
THOMAS R. DANIELS AND MICHAEL WILZ, BOTH OF SAME PLACE.

CAR-COUPLING.

SPECIFICATION forming part of Letters Patent No. 337,508, dated March 9, 1886.

Application filed December 7, 1885. Serial No. 184,906. (No model.)

To all whom it may concern:

Be it known that I, JAMES J. LARGENT, of Peoria, in the county of Peoria, in the State of Illinois, have invented an Improved Car-
5 Coupling; and I do hereby declare that the following is a full, clear, and exact description thereof, reference being had to the annexed drawings, making a part of this specification, in which like letters of reference refer to like parts, and in which—

Figure 1 represents a sectional view at X X in Fig. 3; Fig. 2, a sectional view at Y Y in Fig. 3; Fig. 3, a horizontal section at Z Z in Fig. 2.

This invention is in the line of car-couplings
15 in which the ordinary link and pin is employed, and the pin is held by a movable prop in the draw-head, so that as a link enters the draw-head the prop is pushed back thereby and the pin permitted to drop into the link.

20 My invention relates especially to the following points: first, the construction of a retractile or repressible guide for directing the low-hanging link up into the draw-head; second, to means for holding the link at a suitable
25 height to enter another draw-head; third, the combining with my guide of a removable pin-prop.

To carry out designs I form the interior of the draw-head with an outwardly downward-sloping bottom, upon which the telescopic guide can easily slide, and provide said guide with projections enabling the pin and link to be held thereby, as desired.

In the drawings, H represents the draw-head, formed with the interior sloping bottom, H'. A is the telescopic guide resting upon said inclined bottom H', and B is the prop projecting up from said guide, for supporting the pin P, as in Fig. 1. The front edge of the prop B is
40 made to overhang its base, so as to form one or more link-receiving cavities, C, for holding the link L, as shown in Fig. 2. The upper end of the telescopic guide A is longitudinally slotted, as shown in Fig. 3, and through this slot D' is passed the bolt E, for holding the said guide in the draw-head.

I sometimes make the upper partition, H², of the draw-head removable by means of transversely-dovetailed edges, as represented in
50 Figs. 1 and 2, and hold the same in place by means of the bolt E. By having this partition

removed the inclined bottom H' can be more easily smoothed in finishing up the draw-head after it is cast.

In making my coupling all that is necessary 55 to be done after finishing up the castings is to slide the telescopic guide A backward up into the interior of the draw-head, and to pass the bolt E down through the slot D'.

In using my car-coupling, when it is desired 60 to couple with another draw-head from which a link is hanging, the pin P is raised until the telescopic guide A slides down to its lowest position, at which it is held by the end of the slot D' coming against the bolt E. The pin being 65 now released, it rests upon the prop B. The other draw-head, approaching its link, which may be hanging quite low therefrom, meets the telescopic guide A, and is directed up the sloping face thereof until it comes against the prop 70 B. This impact of the incoming link with said prop pushes the latter and the telescopic guide formed therewith back and up until said prop is away from under the pin P, which at once drops and enters the link. The coupling being 75 thus formed, the coupling-heads or draw-heads are permitted to come against each other by the play which is given to the telescopic guide A, for the slot D' in the end D of said guide I make sufficiently long to enable the guide to be 80 pushed entirely into its draw-head. This repression of the guide may be done by the impact thereagainst of the other draw-head, or by the pressure of the link against the prop B. If it is desired to couple this draw-head with 85 another some little higher, the end of the link L is inserted into one or the other of the cavities C, as in Fig. 2, with the pin down. To have the link held up quite high, the lower of said cavities is used, and if not so high the upper. 90 The link is held by means of the slight elevation C' just in front of said cavities, forming the fulcrum, and the roof of the cavities becoming the weight to hold the inner end of the link down and its outer end up.

I am aware that prior to my invention a car-coupling has been formed with an inclined interior and a pin-prop movable thereon, so that I do not claim the same, broadly; but

What I do claim as my invention, and for 100 which I desire Letters Patent, is as follows, to wit:

1. In a car-coupling, the combination, with the draw-head having the bottom of its interior downwardly inclined to its mouth, of the telescopic guide easily movable upon said inclined bottom, and adapted to have its lower extremity project down and out from the mouth of the draw-head, and to be moved back up therein, whereby to receive and guide a link up into the draw-head, as set forth.
2. In a car-coupling, the combination, with the draw-head having the bottom of its interior inclined, as set forth, of the telescopic guide easily movable on said inclined bottom and having the longitudinal slot, and the bolt in said slot for limiting the displacement of said guide, substantially as and for the purpose set forth.
3. The combination, in a car-coupling, of the draw-head H, having the inclined bottom H' in its interior, the telescopic guide A, having the prop B, and the cavities therein, and having its upper end slotted, and the bolt E in said slot, substantially as and for the purpose set forth. 20

In testimony that I claim the foregoing invention I have hereunto set my hand and seal this 3d day of December, 1885. 25

JAMES J. LARGENT. [L.S.]

In presence of—

A. H. HOLMES,
A. B. UPHAM.
